UNITED STATES PATENT OFFICE

MAURICE A. SMITH, OF JEANNETTE, PENNSYLVANIA, ASSIGNOR TO MCKEE GLASS COMPANY, OF JEANNETTE, PENNSYLVANIA, A CORPORATION OF PENNSYLVANIA

DESIGN FOR A GOBLET

Application filed July 21, 1932. Serial No. 44,397. Term of patent 7 years.

To all whom it may concern:

Be it known that I, MAURICE A. SMITH, a citizen of the United States, residing at Jeannette, in the county of Westmoreland, State of Pennsylvania, have invented a new, original, and ornamental Design for a Goblet, of which the following is a specification, reference being had to the accompanying drawing, forming a part thereof.

Figure 1 is an elevational view of a goblet embodying my new design; Fig. 2 is a vertical sectional view thereof, and Fig. 3 is an inverted plan view.

I claim:

The ornamental design for a goblet, as shown.

MAURICE A. SMITH.
